DESIGN FOR A GAME BOARD

Casimir J. Snaawadzki, Chicago, Ill., assignor of one-fourth to Joseph B. Lee and L. E. Nimschik, and one-half to Philip F. Nimschik and Helen Nimschik, all of Chicago, Ill.

Application January 6, 1937, Serial No. 66,917

Term of patent 14 years

To all whom it may concern:

Be it known that I, Casimir J. Snaawadzki, a citizen of the United States, residing at Chicago, in the county of Cook and State of Illinois, have invented a new, original, and ornamental Design for a Game Board, of which the following is a specification, reference being had to the accompanying drawing forming part thereof, and in which:

Fig. 1 is a plan view of a game board showing my new design; and

Fig. 2 is an end view.

I claim:

The ornamental design for a game board, as shown.

CASIMIR J. SNAWADZKI.
